Primary Examiner — Alison M Ofstun*(74) Attorney, Agent, or Firm* — Greer, Burns & Crain,
Ltd(57) CLAIM

The ornamental design for a hair trimmer, as shown and described.

DESCRIPTION

FIG. 1 is a top perspective view of a hair trimmer;
FIG. 2 is a left side view thereof;
FIG. 3 is a right side view thereof;
FIG. 4 is a front view thereof;
FIG. 5 is a rear view thereof;
FIG. 6 is a top plan view thereof; and,
FIG. 7 is a bottom plan view thereof.
In the drawings, the broken lines illustrate portions of the hair trimmer and form no part of the claimed design.
